UNITED STATES PATENT OFFICE.

FREDERICK J. CLARK, OF BUFFALO, NEW YORK, ASSIGNOR TO EASTMAN MACHINE COMPANY, OF BUFFALO, NEW YORK.

CLOTH-CUTTING MACHINE.

Application filed September 30, 1926. Serial No. 133,658.

This invention relates to cloth cutting machines, and particularly to the support and control of the presser foot thereof.

An object of the invention is to provide an improved cloth cutting machine, in which the movements of the presser foot may be conveniently controlled in a simple manner by the fingers of one's hand while that hand is manipulating the machine; in which the presser foot and its controlling mechanism may be easily and quickly applied to or removed from the machine in a simple manner; in which the presser foot and its controlling mechanism may be formed to a maximum extent from stamped sheet metal and with a minimum of machine operations; in which the presser foot and its controlling mechanism may be assembled with a minimum of attaching members; and in which the presser foot and its supporting and controlling mechanism will be relatively simple, durable, effective, convenient, and relatively inexpensive.

Various other objects and advantages will be apparent from the following description of an embodiment of the invention, and the novel features will be particularly pointed out hereinafter in connection with the appended claims.

30 In the accompanying drawings:

Fig. 1 is a side elevation of a cloth cutting machine having a presser foot and its controlling mechanism constructed in accordance with this invention;

35 Fig. 2 is a front elevation of the same;

Fig. 3 is a front elevation of a presser foot and part of its controlling mechanism, as shown in Fig. 2, but on a somewhat larger scale, and with certain of the parts partially in section to better show certain details;

40 Fig. 4 is a side elevation of part of the machine, as viewed from the side opposite that shown in Fig. 1;

Fig. 5 is an inside elevation of the means for mounting and controlling the presser foot;

45 Fig. 6 is a sectional plan of the same, with the section taken approximately along the line 6-6 of Fig. 5;

50 Fig. 7 is a front elevation of the means for supporting and controlling the presser foot, somewhat similar to Fig. 3, but illustrating the parts in a different relative position; and

55 Fig. 8 is a sectional plan of a portion of the presser foot controlling mechanism, the

section being taken approximately along the line 8-8, of Fig. 4.

In the illustrated embodiment of the invention, the cloth cutting machine includes a standard frame 1 having a relatively flat and thin supporting base 2, which is bevelled or tapered along its forward edge as at 3, so as readily to run beneath a pile of cloth to the cut. A cutting knife 4 is mounted in the standard 1 for vertical reciprocation, with its cutting edge extending forwardly from the standard, and an operating motor 5 carried upon the upper end of the standard frame 1 is connected through suitable mechanism common in the art to the knife 4 for reciprocating the same. A handle 6 extends laterally from the standard frame 1 and in a direction rearwardly from the knife 4, by which the machine may be manipulated and pushed forwardly and turned during the cutting operation. The details just described are old in the art and per se form no part of the present invention.

A bolt 7 extends from side to side through the standard frame 1, and at one side carries 80 a wing nut 8 and at its other side an enlarged head 9 having a pin 10 extended from the under face of the head in a direction parallel to the shank of the bolt for a short distance. The standard frame 1 is provided with an 85 aperture in which the pin 10 slides, so that the bolt will be held against rotation while being free to slide endwise through the standard frame. The standard frame is also provided, in the area through which the bolt 7 90 passes, with a slot or groove 11, the groove extending rearwardly along one face from a forward edge.

One arm of a somewhat L-shaped bracket 12 is provided with a tongue 13 extending 95 from an edge thereof and in its plane, which fits and slides in the groove 11 (see particularly Fig. 4). This tongue is provided with a slot 14 extending inwardly from its free end, and this slot is of such a width and located at 100 such a point as to embrace the shank of the bolt 7 below the head 9 as the tongue moves rearwardly in the groove 11. By tightening the wing nut 8, the bolt 7 may be used to clamp the bracket 12 to one side of the standard, with the bracket 12 extending forwardly therefrom and then crosswise in front of the same. The pin 10 is slidably received in the standard frame 1 at the level of the bolt 7, so that the slot 14 will clear the same as the 110

bracket is attached to or removed from the standard frame.

In the forward face of the free arm of the L-shaped bracket 12, I may provide a vertically extending channel 15, which channel may be closed by a sheet metal plate 16 secured over the channel face of the bracket 12 in any suitable manner, such as by machine screws 17 which pass through the plate and into the bracket. A tongue 18 is struck out from the plate rearwardly at one side of the free end edge of the outer arm of the bracket, and an ear 19 is bent rearwardly from the plate 16 at one side of and parallel to the tongue 18. The tongue is provided with a slot 20 from its free end edge, which in reality divides the tongue 18 into two separate tongues. A bar or plate 21 is inserted edge-wise in the slot 20, so as to rock in the slot 20 upon the slot walls as a fulcrum, one end of the plate or bar 21 extending into close proximity to the ear 19, and the other end of the bar or plate 21 extending beneath the channel of the bracket 12. The latter end of the plate or bar 21 is provided with an aperture or slot 22 through which a spindle 23 of the presser foot 24 passes, the spindle 23 being slidingly confined in the groove 15 by the plate 16. Thus the sliding movements of the presser foot toward and from the cloth being cut will be controlled by the bar or plate 21 which acts thereon in the nature of a clutch, the plate 21 tilting into a position oblique to the spindle to bind the latter against movement, and into a plane normal to the axis of the spindle to release the latter.

When the plate or bar 21 is in a plane normal to the spindle 23, the spindle and its presser foot may reciprocate vertically in either direction without hindrance, but when the plate or bar 21 is rocked about the walls of the slot 20 as fulcrums, it will assume a position slightly oblique or inclined to the spindle 23, and will bind the same in a manner to restrict the endwise movements of the latter. The lower edge of the bracket 12 serves to limit rocking movement of the plate or bar 21 in one direction, and a tongue 25 may be bent rearwardly from the lower edge of the plate 16 beneath the end of the plate or bar 21 through which the spindle passes, so as to limit movement of the plate or bar 21 in the other direction beyond a position in which it is substantially normal to the spindle 23.

A lever 26 is pivoted by a screw 27 to the rearwardly extending ear of the plate 16, and at its end nearest the plate 16 is provided with a slot 28 which extends inwardly from its free end and receives the adjacent end of the bar or plate 21, so that when the lever is rocked, the plate or bar 21 will be rocked into and out of a position in which it binds the spindle 23. The inner end of the slot 28 may be somewhat wider than the entrance end

which embraces the plate or bar 21, so as to avoid binding. The free or rearward end of the lever 26 extends along a side of the standard frame 1, and terminates at a point closely adjacent the handle 6, as shown 70 clearly in Fig. 1, so that it may be engaged and operated by the finger of one's hand which is grasping the handle while manipulating the machine and without removing that hand from the handle. Thus, one may 75 manipulate the machine in the desired manner and at the same time with a finger of the same hand operate the lever 26 to release the spindle 23 and permit the presser foot to fall or rise to maintain in proper engagement 80 with the material being cut.

A leaf spring 29 is secured to an ear 30 which is turned rearwardly from the lower edge of the plate 16. The leaf spring bears beneath the rearwardly extending arm of the 85 lever 26, and yieldingly urges it upwardly which will be in a direction to rock the plate or bar 21 into an oblique position and bind the spindle 23 of the presser foot. The presser foot spindle will thus be normally 90 locked by the clutch plate or bar 21, and may be released by depressing the rear end of the lever 26.

In the use of this machine, the presser foot and its supporting and operating means may be applied as a unit to the standard frame 1 by loosening the bolt 7 and sliding the tongue 13 beneath the head 9 of the bolt 7, and then tightening the wing nut 8. This places the presser foot immediately in front of the cutter 4, and the presser foot is provided with a slot which embraces the cutter 4 from the direction of its cutting edge, and thus the cutter blade 4 reciprocates through the presser foot. The presser foot will normally be held 100 in any adjusted position by the binding action of the plate or bar 21 which is held in an oblique position by the action of the spring 29. One may, while grasping the handle 6, depress the rear end of the lever 26 110 with a finger of the hand grasping the handle 6, which act will rock the plate 21 into a position in which its plane is substantially normal to the spindle 23. This releases the spindle and the latter will fall until it strikes 115 the cloth pile being cut. Upon releasing the lever 26, the spring 29 will, through the lever 26, return the plate or bar 21 into its oblique position in which it locks the spindle 23 against upward movement. The presser foot 120 may be moved upwardly, however, by first depressing the lever 26 to rock the plate or bar 21 into releasing position as limited by the ear 25.

The plate 21, however, allows the spindle 125 23 and presser foot to be pulled downwardly manually with merely some frictional resistance caused by the action of spring 29 in urging the plate or bar 21 into its oblique position.

It will be observed from the foregoing that it is unnecessary to mill teeth in the spindle 23 in order to provide means for locking it in adjusted positions, and the plate 16, lever 26, 5 and plate or bar 21 may all be formed from stamped sheet metal. The assembly of the parts for controlling the presser foot spindle is comparatively simple, because there are very few screws to be used. The attachment 10 or removal of the presser foot and its controlling mechanism as a unit is possible in a simple manner by merely loosening or tightening the bolt 7.

It will be obvious that various changes in 15 the details which have been herein described and illustrated in order to explain the invention may be made by those skilled in the art within the principle and scope of the invention as expressed in the appended claims.

20 I claim as my invention:

1. In a cloth cutting machine, a standard frame, a cutter mounted on said frame for cutting movements, a handle extending from said frame by which the machine may be 25 guided, a bracket member detachably secured to one side face of said frame and having an arm extending around the forward face of the frame, a presser foot having a spindle slidably carried by said arm of the bracket 30 member for movement toward and from the cloth to be cut, a clutch carried by the member and controlling the movements of said spindle relatively to the cloth being cut, and a controlling element for said clutch carried 35 by said member and having an operating arm extending into proximity to the handle so as to be operable by a finger of one's hand while that hand is grasping the handle and manipulating the frame relatively to the cloth.

40 2. In a cloth cutting machine, a standard frame, a cutter mounted on said frame for cutting movements, a handle extending from said frame by which the machine may be guided and manipulated, a bracket member 45 detachably secured to said frame, a presser foot carried by said bracket member for movement from and towards the cloth to be cut and having a spindle, a plate through which said spindle passes, said bracket member having a fulcrum for said plate permitting a limited rocking movement of the plate 50 to bind or release the spindle, and means including an operating member extending in proximity to the handle so as to be operable 55 by a finger of one's hand while that hand is grasping the handle, for rocking the plate into position in which it releases the spindle to permit movement of the latter toward and from the cloth being cut.

60 3. In a cloth cutting machine, a standard frame, a cutter mounted on said frame for cutting movements, a handle extending from said frame by which the machine may be manipulated, a presser foot having a spindle carried 65 by said frame for movement toward and

from the cloth to be cut, a plate having a slot from face to face through which the spindle passes in a direction normal thereto with a limited clearance, said plate being rockably supported by said frame, so as to be movable 70 into and out of a position in which it binds the spindle, and means for rocking the plate in a direction to release the presser foot spindle, including an operating member disposed in close proximity to the handle, whereby the 75 movements of the presser foot may be controlled by the fingers of one's hand while that hand is grasping the handle and manipulating the frame.

4. In a cloth cutting machine, a standard 80 frame, a presser foot mounted for movement toward and from the cloth being cut and having a spindle, a plate rockably mounted on said frame and through which the spindle passes in an approximately normal relation 85 thereto, whereby the plate will have a limited rocking movement between positions in which it binds or frees the spindle, and means for rocking the plate including a controlling member accessible for operation by a finger 90 of one's hand while that hand is grasping the handle and manipulating the frame.

5. In a cloth cutting machine, a frame, a presser foot mounted thereon for movement toward and from the cloth being cut and having a spindle, a plate through which the spindle passes with a slight clearance, said plate being mounted on said frame for rocking movement between positions and in directions 95 in which it binds and frees the spindle, means 100 yielding urging the rocking plate in a rocking direction to bind the spindle and prevent movement of the presser foot, including a controlling member accessible for manipulation from the fingers of one's hand while that 105 hand is grasping the handle and manipulating the frame.

6. In a cloth cutting machine, a frame, a handle by which the frame may be manipulated, a presser foot mounted on said frame for movement toward and from the cloth being cut, and having a spindle extending in the direction of movement, a plate mounted for rocking movement on said frame and through which said spindle extends, whereby the rocking of the plate will bind or free the spindle, said frame having means to limit rocking movement of said plate, and a lever mounted on said frame and having a slot in which the plate is received, said lever having an arm 115 extending into proximity to the handle, whereby the lever may be operated to release the spindle by the fingers of the hand which may be grasping the handle and manipulating the frame without removing the hand from 120 the handle.

7. In a cloth cutting machine, a frame, a handle by which the frame may be manipulated, a presser foot mounted on said frame for movement toward and from the cloth being 130

cut, and having a spindle extending in the direction of movement, a plate mounted for rocking movement on said frame and through which said spindle extends, whereby the rocking of the plate will bind or free the spindle, said frame having means to limit rocking movement of said plate, a lever mounted on said frame and having a slot in which the plate is received, said lever having an arm extending into proximity to the handle, whereby the lever may be operated to release the spindle by the fingers of the hand which may be grasping the handle and manipulating the frame without removing the hand from the handle, and spring means yieldably urging the plate in a direction to bind the spindle.

8. In a cloth cutting machine, a frame, a handle by which the frame may be manipulated, a presser foot mounted on said frame for movement toward and from the cloth being cut, and having a spindle extending in the direction of movement, a plate mounted for rocking movement on said frame and through which said spindle extends, whereby the rocking of the plate will bind or free the spindle, said frame having means to limit rocking movement of said plate, a lever mounted on said frame and having a slot in which the plate is received, said lever having an arm extending into proximity to the handle, whereby the lever may be operated to release the spindle by the fingers of the hand which may be grasping the handle and manipulating the frame without removing the hand from the handle, and a leaf spring carried by the frame and bearing upon an arm of said lever for urging it, and through it the plate, in a direction to bind the spindle.

9. In a cloth cutting machine, a standard frame, a cutter carried by the frame, a handle on the frame by which it may be manipulated, a presser foot mounted on said frame for movement toward and from the cloth being cut and having a spindle extending in the direction of movement, said frame having a wall extending approximately parallel to the spindle and having a slot therein, a plate passing through said slot and rockable upon the walls of the slot as a fulcrum, said plate having also a slot through which the spindle extends, and means for rocking the plate to bind or free the spindle.

10. In a cloth cutting machine, a standard frame, a cutter carried by the frame, a handle on the frame by which it may be manipulated, a presser foot mounted on said frame for movement toward and from the cloth being cut and having a spindle extending in the direction of movement, said frame having a wall extending approximately parallel to the spindle and having a slot therein, a plate passing through said slot and rockable upon the walls of the slot as a fulcrum,

said plate having also a slot through which the spindle extends, and a lever having a slot receiving an arm of the plate, whereby operation of the lever will rock the plate, said lever having an arm extending into proximity to the handle.

11. In a cloth cutting machine, a standard frame, a cutter carried by the frame, a handle on the frame by which it may be manipulated, a presser foot mounted on said frame for movement toward and from the cloth being cut and having a spindle extending in the direction of movement, said frame having a wall extending approximately parallel to the spindle and having a slot therein, a plate passing through said slot and rockable upon the walls of the slot as a fulcrum, said plate having also a slot through which the spindle extends, a lever having a slot receiving an arm of the plate, whereby operation of the lever will rock the plate, said lever having an arm extending into proximity to the handle, and spring means for urging the plate yieldingly in a direction to bind the spindle.

12. In a cloth cutting machine, a standard frame having a handle extending laterally therefrom and by which it may be manipulated, a bolt passing through the frame from face to face, a bracket having a slot, 95 slideable along a face of the frame into and out of embracing relation to the shank of the bolt, whereby it may be clamped into position by tightening of the bolt, a presser foot mounted on said bracket for movement toward and from the cloth being cut, and a clutch device carried by the bracket for controlling the movements of the presser foot and having a controlling member in proximity to the handle for manipulation by a finger of one's hand while that hand is grasping the handle and manipulating the frame.

13. In a cloth cutting machine, a standard frame having a handle extending laterally therefrom and by which it may be manipulated, said frame having a channel extending in a direction toward and from the cloth being cut, and in a direction approximately normal to the plane of the cloth, a plate covering the channel to form therewith a bearing passage, a presser foot having a spindle sliding in said channel, said plate having a slot extending from an edge thereof in a plane transverse to the axis of the spindle, a bar extending through said slot and rockable upon a slot wall as a fulcrum, said bar having a slot through which the spindle passes and by which the spindle may be bound in adjusted positions by rocking of the bar into a position oblique to the axis of the spindle, and means for rocking the bar to free or bind the spindle.

14. In a cloth cutting machine, a standard frame having a handle extending laterally therefrom and by which it may be manipu- 130

lated, said frame having a channel extending in a direction toward and from the cloth being cut, and in a direction approximately normal to the plane of the cloth, a plate covering the channel to form therewith a bearing passage, a presser foot having a spindle sliding in said channel, said plate having a slot extending from an edge thereof in a plane transverse to the axis of the spindle, a bar extending through said slot and rockable upon a slot wall as a fulcrum, said bar having a slot through which the spindle passes and by which the spindle may be bound in adjusted positions by rocking of the bar into a position oblique to the axis of the spindle, means for rocking the bar to free or bind the spindle, and spring actuated means for urging the bar in a direction to bind the spindle, but operable to free the bar when desired.

20 15. In a cloth cutting machine, a standard frame having a handle extending laterally therefrom and by which it may be manipulated, said frame having a channel extending in a direction toward and from the cloth being cut, and in a direction approximately normal to the plane of the cloth, a plate covering the channel to form therewith a bearing passage, a presser foot having a spindle sliding in said channel, said plate having a slot extending from an edge thereof in a plane transverse to the axis of the spindle, a bar extending through said slot and rockable upon a slot wall as a fulcrum, said bar having a slot through which the spindle passes and by which the spindle may be bound in adjusted positions by rocking of the bar into a position oblique to the axis of the spindle, and a lever pivoted to said plate and having a slot receiving the bar, whereby the bar may be rocked to bind or free the spindle by operation of said lever.

30

35

40

16. In a cloth cutting machine, a standard frame having a handle extending laterally therefrom and by which it may be manipulated, said frame having a channel extending in a direction toward and from the cloth being cut, and in a direction approximately normal to the plane of the cloth, a plate covering the channel to form therewith a bearing passage, a presser foot having a spindle sliding in said channel, said plate having a slot extending from an edge thereof in a plane transverse to the axis of the spindle, a bar extending through said slot and rockable upon a slot wall as a fulcrum, said bar having a slot through which the spindle passes and

by which the spindle may be bound in adjusted positions by rocking of the bar into a position oblique to the axis of the spindle, a lever pivoted to said plate and having a slot 60 receiving the bar, whereby the bar may be rocked to bind or free the spindle by operation of said lever, and a spring acting upon said lever to urge it yieldingly in a direction to bind the spindle. 65

17. In a cloth cutting machine, a standard frame having a handle extending laterally therefrom and by which it may be manipulated, said frame having a channel extending in a direction toward and from the cloth being cut, and in a direction approximately normal to the plane of the cloth, a plate covering the channel to form therewith a bearing passage, a presser foot having a spindle sliding in said channel, said plate having a slot extending from an edge thereof in a plane transverse to the axis of the spindle, a bar extending through said slot and rockable upon a slot wall as a fulcrum, said bar having a slot through which the spindle passes and by which the spindle may be bound in adjusted positions by rocking of the bar into a position oblique to the axis of the spindle, and a lever pivoted to said plate and having a slot receiving the bar, whereby the bar may be rocked to bind or free the spindle by operation of said lever, said lever having an arm extending into proximity to the handle, 70 75 80 85 90

18. In a cloth cutting machine, a standard frame having a handle extending laterally therefrom and by which it may be manipulated, said frame having a channel extending in a direction toward and from the cloth being cut, and in a direction approximately normal to the plane of the cloth, a plate covering the channel to form therewith a bearing passage, a presser foot having a spindle sliding in said channel, said plate having a slot extending from an edge thereof in a plane transverse to the axis of the spindle, a bar extending through said slot and rockable upon a slot wall as a fulcrum, said bar having a slot through which the spindle passes and by which the spindle may be bound in adjusted positions by rocking of the bar into a position oblique to the axis of the spindle, a lever pivoted to said plate and having a slot receiving the bar, whereby the bar may be rocked to bind or free the spindle by operation of said lever, said lever having an arm extending into proximity to the handle. 90 95 100 105 110
